CLAIM

The ornamental design for a headband, as shown and described.

DESCRIPTION

FIG. 1 is a perspective view of a headband showing my new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof, which has been folded and secured by straps.

The broken lines depict environment and are included for the purpose of illustrating only and form no part of the claimed design.
